UNITED STATES PATENT OFFICE.

AUSTIN FLEEGER, OF CHICORA, PENNSYLVANIA.

JOINT FOR ELECTRIC CONDUCTORS AND OTHER WIRES.

No. 831,548.

Specification of Letters Patent.

Patented Sept. 25, 1906.

Application filed August 18, 1905. Serial No. 274,701.

To all whom it may concern:

Be it known that I, AUSTIN FLEEGER, a citizen of the United States, residing at Chicora, in the county of Butler and State of Pennsylvania, have invented certain new and useful Improvements in Joints for Electric Conductors and other Wires, of which the following is a specification, reference being had therein to the accompanying drawings.

This invention relates to joints for electric conductors and other wires, and has for its object to provide a simple and efficient means for quickly and firmly uniting the ends of such conductors or wires and holding them thus united while under tension.

The invention is in the nature of an improvement upon the construction set forth in Letters Patent of the United States, granted to me December 12, 1905, No. 806,789. In that application there is set forth a construction in which the ends of the wires are provided with enlarged terminal portions which may be interlocked or intertwined, said ends being inclosed in a sleeve of ductile metal which is swaged down upon them at its ends. This joint requires special preparation of the ends of the wires and also requires the use of a swaging-tool at the place where the joint is formed.

It is the object of my present invention to do away with the necessity of using a swaging-tool during the operation of uniting the ends of the wires and to dispense with the necessity of specially preparing the ends of the wires, so that the ends of the wires may be united by the mere act of inserting them in the coupling device, while at the same time the ends of the wires lying within the coupling device are entirely inclosed and protected, the coupling device being formed in a single piece without any separable joints of any kind and without any openings except those through which the wires enter.

To these ends my invention consists in certain novel features which I will now proceed to describe and will then particularly point out in the claims.

In the accompanying drawings, Figure 1 is a perspective view of the coupling-sleeve in its original or first condition before being swaged down. Fig. 2 is an elevation of a completed joint. Fig. 3 is a longitudinal sectional view of what is shown in Fig. 2, illustrating one embodiment of my invention. Fig. 4 is a view similar to Fig. 3, illustrating a

modified form of my invention. Fig. 5 is an enlarged detail perspective view of one set of the gripping-jaws shown in Fig. 4. Fig. 6 is a detail sectional view of the same, taken on the line $x-x$ of Fig. 5 and looking in the direction of the arrows. Fig. 7 is a similar view taken on the line $y-y$ of Fig. 5 and looking in the direction of the arrows. Fig. 8 is a view similar to Fig. 3, illustrating yet another modification. Fig. 9 is an enlarged detail view of one set of the gripping-jaws shown in Fig. 8 in the form which is given to it before its insertion into the coupling-sleeve; and Fig. 10 is a detail sectional view of the same before it is given the form shown in Fig. 9.

My present invention contemplates the employment of a sleeve of ductile metal—such as brass, copper, steel, or iron—which in its original form is preferably a cylindric tube of equal diameter throughout its length, said sleeve having no lateral openings and being imperforate, the only opening being the longitudinal one extending through it from end to end. Within this sleeve are placed gripping devices, and the ends of the sleeve are then swaged down to give them a tapering or frusto-conical form, both internally and externally, until the openings at the ends of the sleeve are of a size corresponding with that of the wire to which they are to be applied. These openings are of less diameter than the gripping devices, so that the gripping devices are permanently held within the sleeve, and the tapering or outwardly-converging walls of the ends of the sleeve coöperate with the gripping devices when these latter are moved outward by the tension on the wires with which they are engaged, thereby causing said gripping devices to firmly grip and hold the ends of the wires, the intensity of their gripping action being proportionate to the strain on the wires and increasing as said strain increases.

Referring first to that form of my invention illustrated more particularly in Figs. 1, 2, and 3, 1 indicates a hollow sleeve or tube of brass or other ductile conducting metal. In its original form (shown in Fig. 1) said sleeve is a cylindric tube of equal diameter throughout its length. When the sleeve is in this condition, I insert therein a plurality of angular bodies 2 (shown in Fig. 3) these angular bodies being of any suitable material—such as steel, brass, copper, or iron—and being sufficiently small to have free play within the sleeve, their sharp angular edges being adapt-

ed to form gripping-teeth which act in the manner hereinafter described. After these angular bodies, which in this case constitute the gripping devices, have been introduced 5 into the sleeve, the ends of the sleeve are swaged down so that they converge outwardly, being given the tapering or frusto-conical form shown at 3 in Figs. 2 and 3, and their terminal apertures 4 being reduced to the 10 size of the wire to which it is intended to apply the coupling, the best results being obtained by constructing a special size of sleeve for each size of wire. The coupling device is then complete and ready for use, it being understood 15 that the gripping bodies are of greater diameter than the end apertures 4 of the sleeve after it has been swaged down, so that the bodies are permanently retained within the sleeve and the sleeve is entirely closed, except for the end apertures, to receive the wires, 20 its body being without separable joint or union of any kind. The wires to be united are indicated by the reference-numeral 5, and their union is effected by holding the sleeve in a vertical position and inserting one of the 25 wires through the aperture in the lower end thereof. After this wire has thus been inserted to a sufficient distance the wire is drawn slightly outward or backward, whereupon 30 some of the angular bodies which constitute the gripping devices will become wedged in between the wire and the tapering wall of the sleeve and will firmly grip and hold the wire, increasing their grip as the pull 35 on the wire increases. When one of the wires has been thus engaged, the sleeve is inverted and those of the gripping-bodies which are free will fall to what is now the lower end of the sleeve, and the other wire is then inserted 40 and engaged or gripped in the same manner as the first wire. The sleeve is then released and the tension on the two wires holds them firmly gripped within the sleeve. It will be noticed that the ends of the wires are entirely inclosed and protected, there being no 45 openings in the sleeve except the end openings which are closed by the wires 5. It will also be noted that the uniting of the wires is effected in a very simple manner, there being no screw-joints or other connections which require manipulation, the wires being gripped by the mere act of inserting them with the sleeve in proper position, and the sleeve having a continuous imperforate body formed in 50 a single piece. The release of the wires may be readily effected by either gaining enough slack by drawing the wires toward each other or by cutting one of the wires near the sleeve so as to permit the sleeve to be turned to an 55 upright or inclined position, whereupon each wire may be released by pushing it downward and inward into the sleeve until the gripping devices release their hold and drop so as to free the wire.

60 65 The fundamental idea of the invention is

the employment of a continuous or imperforate sleeve into which the gripping devices are first inserted, after which the ends of the sleeve are swaged down to the tapering form described.

The form and structure of the gripping devices may be modified, and although I prefer the form which I have just described and which is shown in Fig. 3 I have illustrated other forms of gripping devices. In Figs. 4 to 7, inclusive, the gripping devices consist of two sets of gripping-jaws, one for each end of the tube, which are introduced while the sleeve is still in its cylindric form and which are held therein by the swaging down of the 70 ends of the sleeve. In this construction each set of gripping-jaws, one of which is shown in detail in Figs. 5, 6, and 7, comprises two jaws 75 6, the two when assembled being frusto-conical in shape, so that each is substantially in 80 the form of a half of a cone divided axially. Each jaw has a longitudinal groove 7 on its inner face provided with teeth 8, so constructed as to permit the wire to move inward and to engage with and prevent outward movement of the wire. These jaws correspond in taper with the ends of the sleeve when swaged down, so far as their main or body portions are concerned, their inner extremities being preferably tapered in the opposite direction, 85 as indicated at 9. In order to maintain them in proper relation to each other and at the same time give them a pivotal or hinged relation in their movements toward and from each other, I provide one of the jaws with 90 notches or recesses 10 in its inner face, the other jaw having corresponding ribs 11, which seat in the notches 10 and prevent independent longitudinal movements of the 95 jaws, while the notches and ribs are so rounded off as to act as a hinged connection between the jaws. The reverse taper of the inner end of each set of jaws permits this hinging or pivotal motion, said inner end being substantially the same diameter as the interior of the 100 sleeve. After the coupling device has been completed by the insertion of the gripping-jaws and the swaging down of the ends of the sleeve the wires to be united are inserted through the ends of the sleeve and between 105 the gripping-jaws of each set, whereupon tension on the wires to draw them outward will cause the teeth of the gripping-jaws to engage the wires, and said jaws will be drawn into the tapering ends of the sleeve and will 110 be thereby forced firmly into engagement with the wires, their grip increasing with the 115 pull of the wires.

In Figs. 8, 9, and 10 I have illustrated another form of gripping-jaws in which each set 120 of jaws is made in a single piece of resilient material, being so arranged as to tend to grip the wires as soon as the wires enter between the jaws. In this construction each set of gripping-jaws consists of a body 12, having a 125 130

longitudinal aperture 13 for the passage of the wire and slotted, as indicated at 14, to form toothed jaws 15, which taper outwardly toward the point. Before introducing these gripping-jaws into the sleeve their free ends are brought toward each other, as illustrated in Fig. 9, until they are separated by a distance somewhat less than the diameter of the wire, the resilience of the material tending to cause them to return to this position when forced apart. When the coupling device is completed by inserting these gripping-jaws and swaging down the ends of the sleeve, the operation is similar to that just described in connection with the construction shown in Figs. 4 to 7, inclusive, except that it is necessary to slightly taper the ends of the wires, as indicated at 16, in order to enable them to enter between the jaws, and the jaws take hold and grip the wires as soon as they are inserted. With this construction there can be no failure of the gripping-jaws to properly engage the wires after these latter have once been inserted between the jaws, the jaws taking hold of the wire by their resilience, so that the position of the sleeve is immaterial, and the gripping-jaws will be drawn into the conical end of the sleeve even when the sleeve is vertical and the engaging movement of withdrawal of the wire is in an upward direction.

As hereinbefore stated, I prefer to construct the sleeves of different sizes, corresponding with the sizes of wire with which they are to be used; but one of the advantages of the construction illustrated in Fig. 3 is that it can in case of emergency be used with any size of wire smaller than the end apertures of the sleeve.

I do not wish to be understood as limiting myself strictly to the precise details of construction hereinbefore described, and shown in the accompanying drawings, as it is obvious that these details may be modified without departing from the principles of my invention.

Having thus fully described my invention, what I claim as new, and desire to secure by Letters Patent, is—

1. A joint for electric conducting-wires and other wires, comprising an integral sleeve of ductile conducting metal provided

with internal gripping devices free to move therein, the ends of said sleeve being swaged down to a tapering or conical form and said sleeve being imperforate except for its end 55 openings, which are smaller than the gripping devices and are adapted to receive the ends of the wires to be united, said gripping devices engaging between the tapering end walls of the sleeve and the alined ends of the 60 wires to hold these latter against outward motion, substantially as described.

2. A joint for electric conducting-wires and other wires, comprising an integral sleeve of ductile conducting metal provided 65 with internal gripping devices free to move therein, said sleeve being imperforate except for its end openings, which are smaller than the gripping devices and are adapted to receive the ends of the wires to be united, said gripping devices engaging between the tapering end walls of the sleeve and the alined ends of the wires to hold these latter against outward motion, said gripping devices consisting of a plurality of free angular bodies 70 75 having sharp engaging edges, substantially as described.

3. A coupling for the ends of wires comprising an integral sleeve of ductile metal, imperforate except at its ends, having gripping devices in its interior free to move therein, and having its ends swaged to a tapering or conical form, the gripping devices being adapted to engage between the tapering inner end walls of the sleeve and the ends of 80 85 the wires which are inserted through the end apertures, substantially as described.

4. A coupling for the ends of alined wires, comprising an integral sleeve of ductile metal, imperforate except at its ends, the end 90 portions of said sleeve being swaged down to a tapering form, and a plurality of angular bodies provided with gripping edges and free to move within said sleeve, the end apertures of the sleeve being of less diameter than said 95 bodies, substantially as described.

In testimony whereof I affix my signature in presence of two witnesses.

AUSTIN FLEEGER.
